SUTURE CUTTER

Clinton M. Cummings, Fairfield, Conn., assignor to The Acme Shear Company, Bridgeport, Conn., a corporation of Connecticut

Filed Feb. 11, 1965, Ser. No. 83,783

Term of patent 14 years

(Cl. D83—12)

FIG. 1.

FIG. 2.

FIG. 3.

FIG. 4.

FIG. 1 is a front elevation of a suture cutter showing my new design, the same being shown in closed position;

FIG. 2 is a side elevation;

FIG. 3 is a front elevation in open position; and

FIG. 4 is a sectional view on an enlarged scale, taken along the line 4—4 of FIG. 1.

The rear elevations in the closed and open positions are identical to the front elevations shown in FIGS. 1 and 3.

The characteristic feature of my design resides in the outwardly curved symmetrically arranged shank portions in combination with the pivoted planar portions of the blade members as best illustrated in FIGS. 1 and 3.

I claim:

The ornamental design for a suture cutter, substantially as shown and described.
